UNITED STATES PATENT OFFICE

2,514,563

ELECTRIC HOIST STRUCTURE

Earl Todd, Kokomo, Ind., assignor to Aerl, Inc.,
Indianapolis, Ind., a corporation

Application September 21, 1946, Serial No. 698,514

3 Claims. (Cl. 187—9)

1

This invention relates to a portable hoist structure.

The chief object of this invention is to provide a hoist structure which is comparatively simple, compact and positive in operation both for elevating and lowering purposes and which may be of portable character and which further may be of safety stop character.

The chief feature of the invention resides in electrically raising and lowering a platform or the like by means of a motor movable therewith, the platform and the like being slidably associated with a pair of spaced uprights and the motor being operatively associated with an intermediate and parallel screw, the screw, uprights and the like comprising a vertical frame portion supported at its lower end by a base which may or may not be of portable type, as desired.

Other objects and features of the invention will be set forth more fully hereinafter.

The full nature of the invention will be understood from the accompanying drawings and the following description and claims.

In the drawings:

Fig. 1 is a perspective view of a portable type embodiment of the invention.

Fig. 2 is a vertical sectional view of the vertical frame, the associated platform portion and the motor drive.

Fig. 3 is a top plan view of a bracket portion comprising the platform proper support and the motor proper support.

In Fig. 1 of the drawings 10 indicates a substantially U-shaped base structure which, at opposite ends of the arms, is provided with casters 11. A forwardly and medianly projecting tongue 12 rotatably supports a swiveling type caster 13 with which is associated a handle 14 so that the entire device is portable and can be moved from one location to another for transference of a load from one location to another.

Rigidly secured at their lower ends to the base 10 are a pair of parallel tubes 15, and same may be suitably secured thereto by means of the bracket portion 16 which, intermediate the tubes, provides a bearing 17 for an intermediate parallel screw 18.

The upper ends of the tubes and the screw are suitably connected together by the parallel upper bracket member 19. The screw is retained against rotation in the brackets 17 and 19 by any suitable means. Either carried by the base bracket 16 or the base immediately adjacent thereto is

2

a down limit safety switch actuator 20, as desired.

Similarly the upper bracket 19 may mount an upper limit travel switch actuator structure 21. Reference will be had thereto hereinafter.

Preferably these actuators are of the yielding pressure type so that when limit switches carried by the movable platform, hereinafter to be described, are engaged at the uppermost elevation or the lowermost elevation, the electric motor, also to be described, is deenergized and automatically conditions the reverse circuit for motor reverse operation although the same is not effected until the circuit is manually closed by the operator, as more fully pointed out hereinafter.

In Figs. 2 and 3, more particularly, there is illustrated a pair of vertically disposed spaced sleeves 22, the same being rigidly connected together as at 23, and extending from the lower end of said sleeves is the laterally directed portion 24. Extending oppositely and substantially contemporaneously with the sleeves 22 is the base plate portion 25.

To the same is detachably mounted a motor 26, see Fig. 2, having upwardly directed shaft 27 carried by the rotor. The laterally disposed portion 24 may be of U-shaped form and may support a suitable platform arrangement, and this may be of any desired type or construction.

The central portion of the rigid connection 23 is preferably centrally apertured as at 28 to freely pass or accommodate the screw 18. The tubular guides 22 obviously are slidably supported upon the tubular uprights 15.

Referring more particularly to Fig. 2, it will therein be noted that a housing structure is provided comprising the lower half portion 29 and an upper half portion 30, the same being suitably secured together as at 31.

The lower portion 29 of this housing structure is centrally disposed between the two sleeves, as it were, although above the same. The housing includes a pair of aligned openings 32, the same freely passing the aforesaid screw 18.

In spaced relation thereto and in alignment with the motor shaft 27 is an opening 33 in the lower housing member 29. Rigid with the end of the shaft 27a, enclosed within the housing aforesaid, is a pinion gear 34. It is suitably supported by upper and lower anti-friction structures 35 and 36.

Interposed between the two openings 32 and in alignment therewith are the anti-friction structures 37 and 38 respectively, and interposed between these bearings is a nut structure 39 having

an internal thread portion 40, the same having threaded engagement with the screw 18.

The exterior of this nut structure 39 includes the toothed arrangement 41, the same meshing with the teeth of the pinion 34. Herein the pinion is smaller than the nut structure so that in effect this direct drive from the motor to the nut structure is of speed reducing type.

The motor 26 is of reversible type and the nut and thread arrangement may be of self-locking character, as it were, or the meshing engagement between the pinion and the nut may be of helical type and thus may also be of reversible or self-locking character.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claims.

The invention claimed is:

1. In a hoist structure having a base, a frame means comprising a pair of substantially spaced, parallel, vertically disposed elongated guide members, means at the top connecting the guide members together, means at the bottom rigidly connecting the guide members together, and an elongated screw member similarly disposed therebetween and supported by said means at the opposite ends, the combination of platform means, elongated sleeves rigid therewith at one end of the platform means and slidably on said guide members, nut means rotatably supported by the platform means and supported thereby and hav-

10

ing threaded connection with the screw member, reversible electric motor means supported by the platform means at one end and movable therewith, and speed reducing means connecting the

5 motor means and nut means together for platform elevation and lowering, the electric motor means and speed reducing means being disposed in outboard relation relative to the platform means, the latter extending oppositely therefrom.

2. A hoist structure as defined by claim 1 wherein the speed reducing means comprises a gear rigid with the motor rotor shaft, and said nut means has a cooperating gear exterior meshing with that rotor shaft mounted gear.

3. A hoist structure as defined by claim 1 wherein there is provided a housing rigid with the upper ends of the sleeves and a plurality of pairs of vertically spaced anti-friction bearings are disposed in the housing, the pairs being laterally spaced, said housing having a pair of aligned openings registering with one pair of bearings and another opening registering with another pair of aligned bearings for the purpose described.
